UNITED STATES PATENT OFFICE

157,885

RADIANT CONVECTOR BASEBOARD PANEL OR THE LIKE

Malcolm W. McRae, Park Ridge, and Joseph D. Pierce, Evanston, Ill., assignors to Crane Co., Chicago, Ill., a corporation of Illinois

Application October 29, 1947, Serial No. 142,179

Term of patent 14 years

(Cl. D81—21)

To all whom it may concern:

Be it known that we, Malcolm W. McRae and Joseph D. Pierce, citizens of the United States and residents of Park Ridge and Evanston, Illinois, respectively, have invented a new, original, and ornamental Design for Radiant Convector Baseboard Panels or the like, of which the following is a specification, reference being had to the accompanying drawing, forming part thereof.

Fig. 1 is a front perspective view of a radiant convector baseboard panel or the like embodying our new design.

Fig. 2 is a rear perspective view of the same.

We claim:

The ornamental design for a radiant convector baseboard panel or the like, substantially as shown.

MALCOLM W. MCRAE.
JOSEPH D. PIERCE.
